SAFETY DEVICE FOR HOISTS OR LIFTS

Cyrus J. Bristol, Des Moines, Iowa, assignor to
The Wayne Pump Company, Fort Wayne, Ind.,
a corporation of Maryland

Application July 11, 1945, Serial No. 604,407

6 Claims. (Cl. 254—93)

1

This invention pertains to elevators or lifts. It is an object of this invention to provide a new and improved safety device for hoists or lifts.

Another object of the invention is to provide a safety leg for a hoist which moves to inoperative position as the hoist lowers, after having been moved a predetermined distance from safety position.

Another object of the invention is to provide a safety device for a hoist or lift, which device is installed wholly above ground and prevents rotation of the hoist or lift.

Another object of the invention is to provide a safety device for a hoist or lift which can be as easily installed after the hoist or lift has been installed as when the hoist or lift is being installed.

Another object of the invention is to provide a safety device for a hoist or lift which is so constructed and arranged that the safety member never touches the floor (or ground) while the hoist or lift is being moved to raised or lowered positions.

Another object of the invention is to provide a safety and non-rotating device for a hoist so constructed and arranged that the device is adapted to be moved through a relatively small angle to condition it for hoist lowering operation.

With these and various other objects in view, the invention may consist of certain novel features of construction and operation as will be more fully described and particularly pointed out in the specification, drawings and claims appended hereto.

In the drawings, which illustrate embodiments of the device and wherein like reference characters are used to designate like parts—

Figure 1 is a fragmentary side elevation of a form of safety mechanism embodying the invention, the view showing the same in various positions of operation; and

Figure 2 is a fragmentary top plan view of the safety mechanism illustrated in Figure 1.

As shown in the drawings a movable safety leg is provided to hold a hoist structure in its elevated position.

In order to safeguard the operator from accidental descent of the lift from raised position, a safety leg is provided which is automatically raised to operative position when the lift is raised. The upper end of the safety leg is connected to the bracket 170 which is shown as secured to the bracket 156 on the hoist superstructure 162. A safety leg may be either a single member such as the tube 172 or may be a frame structure. The

2

operation, of course, would be the same in either case, and only the single tube structure is described. The tube 172 is pivoted as at 174 to the spaced arms 176 and 178 of bracket 170, and tube 172 is provided with the bracket 180 pivoted as at 182 to the rod 184 which is slidably received or telescopes into the pipe 186. Said pipe 186 is provided with the legs 188, braced at 190 and pivoted as at 192 to the lugs 194 of bracket 196 provided on the floor or ground, pivot 192 being preferably in vertical alignment with the pivot 182 when the safety leg is in operative or full line position 172d as illustrated in Figure 1. When the assembly 180, 184, 186, 188, 196 is used the hoist cannot be rotated about its vertical axis.

Tube 172 is provided with the locking pin or member 198 adapted to engage within the slot 200 of the locking or latch member 202, member 202 being fixedly mounted to the shaft 204 journaled at one end in arm 178 of bracket 170, and journaled in lug 206 also provided on bracket 170, the shaft being provided with the operating handle or lever 208 which may be disposed within the rails or outside of the adjacent rail of the superstructure. The slot 200 is provided with the locking shoulder 210 adapted to receive the pin 198 to lock the tube 172 in position 172c for permitting lowering of the lift and rendering the safety leg inoperative during the lowering operation.

When the hoist is raised from its lowered position the safety leg will move from inoperative position where it is horizontal, as at 172a (Figure 1) to the full operative position as shown at 172d, and in this case the pin 198 will have moved past the shoulder 210 into the elongated recess 200a. In so moving pin 198 will not engage shoulder 210 because due to the weight of lever 208 and member 202 the pin will travel along the top edge of its slot to the full line position shown in Figure 1 wherein the safety leg is vertical. When it is desired to lower the lift, the lever 208 must first of all be moved in a counter-clockwise direction (Figure 6) to the latched or dotted line position as shown at 208a where the pin 198 will engage the shoulder 210. This movement will be permitted, due to the telescopic connection between the rod 184 and pipe 186. When the operation of the hoist or lift is reversed and the superstructure moves downwardly it will be seen that pivot 174 moves vertically downwardly as does pivot 182 until rod 184 has telescoped into tube 186, at which time pivot 182 will pivot around pivot 192 preventing the end of leg 172 from touching the ground, and causing it to move

through positions 172c and 172b, until finally it is in position 172a, at which time the superstructure is in its lowermost position. Up until the time that rod 184 has telescoped into tube 186, the pin 198 has been in latched position, that is, in engagement with shoulder 210. After rod 184 has been received in tube 186 and as the lift descends moving the leg from 172b toward 172a, the latch becomes unlatched as the telescoped rod 184 and tube 186 cause pin 198 to move from shoulder 210 into engagement with the top edge of slot 200.

It is to be understood that this application is not to be limited by the exact embodiments of the device shown, which are merely by way of illustration and not limitation, as various and other forms of the device will, of course, be apparent to those skilled in the art without departing from the spirit of the invention or the scope of the claims.

I claim:

1. In a hoist, the combination of a superstructure, means for raising and lowering said superstructure, safety mechanism movable from an inoperative position to an operative position when said superstructure is raised, said safety mechanism comprising a rigid member pivoted adjacent the upper end thereof to the hoist, a latch member inoperative when the hoist is being raised but being movable to move the rigid member from operative position to an intermediate position, a telescopic member pivoted at one end to the rigid member and at the other end to a point fixed with respect to the superstructure, said telescopic member collapsing a predetermined amount as the hoist is lowered and thereafter moving the rigid member to inoperative position as the hoist is lowered to a position substantially parallel to the superstructure.

2. In a hoist, the combination of a superstructure, means for raising and lowering said superstructure, safety mechanism movable from an inoperative position to an operative position when said superstructure is raised, said safety mechanism comprising a rigid member pivoted adjacent the upper end thereof to the hoist, a latch member inoperative when the hoist is being raised but being movable to move the rigid member from operative position to an intermediate position, a telescopic member pivoted at one end to the rigid member and at the other end to a point fixed with respect to the superstructure, said telescopic member collapsing a predetermined amount as the hoist is lowered and thereafter releasing said latch and moving the rigid member to inoperative position as the hoist is lowered to a position substantially parallel to the superstructure.

3. In a hoist, the combination of a superstructure, means for raising and lowering said superstructure, said means having a portion fixed as in the ground, safety mechanism interposed between said superstructure and the ground movable from an inoperative position to an operative position when said superstructure is raised, said safety mechanism comprising a rigid member pivoted adjacent the upper end thereof to said hoist, a latch member pivoted to said hoist adjacent the pivot of said rigid member, a locking member on said rigid member, said latch member having a part movable with said latch member to engage the locking member and hold said rigid member at an angle to the horizontal, and a member pivoted to said rigid member and to means fixed with respect to said superstructure

to move the rigid member to substantially a horizontal position when the superstructure is in a fully lowered position, movement of said rigid member from the angular position in which it is held by the latch and locking members serving to render said latch and locking members inoperative.

4. In a hoist, the combination of a stationary casing adapted to be substantially buried in the ground, a slideable plunger mounted in said casing, an operating medium for raising and lowering said plunger, load carrying superstructure carried by said plunger, safety mechanism interposed between said superstructure and the ground adapted to be positioned to prevent accidental lowering of said superstructure, said safety mechanism comprising a rigid member pivoted adjacent the upper end thereof to said hoist and of a length less than the distance between the pivot and the ground when the hoist is in fully raised position whereby when the hoist is in fully raised position the rigid member is vertically disposed, a latch member pivoted to said hoist adjacent the pivot of said rigid member, a locking member on said rigid member, said latch member having a part cooperating with said locking member when said latch member is inoperative to permit the rigid member to engage the ground to prevent lowering of the hoist, said latch member having a second part movable with said latch member to engage the locking member and hold said rigid member at an angle to the horizontal, and a member pivoted to said rigid member and to means fixed with respect to said superstructure to move the rigid member toward substantially a horizontal position when the superstructure is being moved toward fully lowered position, movement of said rigid member from the angular position in which it is held by the latch and locking members serving to render said latch member inoperative by moving the locking member out of engagement with the second part of the latch member and into cooperating relation with the first named part of the latch member.

5. In a hoist, the combination of a stationary casing adapted to be substantially buried in the ground, a slideable plunger mounted in said casing, operating medium for raising and lowering said plunger, load carrying superstructure carried by said plunger, safety mechanism interposed between said superstructure and the ground adapted to be positioned to prevent accidental lowering of said superstructure, said safety mechanism comprising a rigid member pivoted adjacent the upper end thereof to said hoist and of a length less than the distance between the pivot and the ground when the hoist is in fully raised position whereby when the hoist is in fully raised position the rigid member is vertically disposed, a latch member pivoted to said hoist adjacent the pivot of said rigid member, a locking member on said rigid member, said latch member having a part cooperating with said locking member when said latch member is inoperative to permit the rigid member to engage the ground to prevent lowering of the hoist, said latch member having a second part movable with said latch member to engage the locking member and holding said rigid member at an angle to the horizontal, and a structure interposed between said rigid member and the ground, said structure comprising telescopically arranged members movable to a predetermined position to form a rigid structure, one of the telescopic members being pivoted

adjacent the upper end of the structure to said rigid member, another of the telescopic members being pivoted to the ground whereby said structure is adapted to move the rigid member toward substantially a horizontal position when the superstructure is being moved toward fully lowered position, movement of said rigid member from the angular position in which it is held by the latch and locking members serving to render said latch member inoperative by moving the locking member out of engagement with the second part of the latch member and into co-operating relation with the first named part of the latch member.

6. In a hoist, the combination of a superstructure, means for raising and lowering said superstructure, safety mechanism movable from an inoperative position when said superstructure is in lowered position to an operative position when said superstructure is raised, said safety mechanism comprising a rigid member pivoted to said hoist by a pivotal connection between said rigid member and hoist, a latch member pivoted to said hoist by a pivotal connection, the axes of said pivotal connections being spaced apart and parallel, said latch member being movable to hold said rigid member in a position other than vertical when said superstructure is raised, and means pivoted to said rigid member for causing said rigid member to pivot around said pivotal connection between the rigid member and hoist

to move to inoperative position as the hoist is lowered, said last named means including telescopic members, one of said members being pivoted to said rigid member and the other of said members being pivoted below said rigid member when said rigid member is in inoperative position with the superstructure lowered, said telescopic members being relatively extensible when the latch is latched and moving to inextensible position to unlatch said latch as the superstructure is being lowered.
